UNITED STATES PATENT OFFICE.

STEPHEN R. FETNER, OF ALBANY, GEORGIA.

SASH FASTENER.

Application filed February 25, 1922. Serial No. 539,060.

To all whom it may concern:

Be it known that I, STEPHEN R. FETNER, a citizen of the United States, residing at Albany, in the county of Dougherty and 5 State of Georgia, have invented new and useful Improvements in Sash Fasteners, of which the following is a specification.

This invention relates to sash fasteners, and has for its primary object to provide 10 means of a simplified and improved nature operable automatically when the window sashes have been moved a predetermined distance to hold or maintain the sashes against further movement in either direction.

15 A further object of the invention is to provide sash fastening means of such construction as to be wholly automatic in their locking or fastening operations and which require no manual effort in securely fastening the sashes.

20 A still further and particular object of the invention is to provide sash fastening means so arranged upon the sash as to be wholly out of sight from the exterior of the 25 window thereby to a degree rendering the window burglar proof.

A still further object of the invention is 30 to provide a lock for the sashes of windows which shall present no outwardly projecting portions to hinder opening of the window to its fullest extent or to damage or mar the window framing in such operation.

With these and other objects in view, the 35 invention consists of the features of construction, combination and arrangement of parts, hereinafter fully described and claimed, reference being had to the accompanying drawing, in which:—

Figure 1 is a sectional view through the 40 meeting rails of the outer and inner sashes of a conventional form of window, and illustrating as applied thereto a locking mechanism constructed in accordance with the invention.

45 Figure 2 is a face view of the locking member carried by one of the sashes,

Figure 3 is a similar view of the sash rail carrying the lock releasing device,

50 Figure 4 is a face view of the sash rail carrying the keeper,

Figure 5 is a perspective view of the latch member removed from its housing, and

55 Figure 6 is a fragmentary perspective view of the latch housing.

Referring now more particularly to the

drawing, the meeting rails of the window include the bottom rail 6 of the outer sash and the top rail 7 of the inner sash; the abutting faces thereof being inclined as shown to make a substantially air and water tight joint when the two rails are brought together in proper manner. The invention, in the present instance, is carried out by arranging the cooperating locking members to be hereafter described upon the meeting rails of the sashes, in order that the latter may be held securely together when in proper closed position.

The lower rail 6 of the outer sash is provided upon its inner or beveled surface with a keeper indicated generally at 8, adapted to cooperate with means to be hereafter described upon the rail 7 of the inner sash to securely lock the said sashes against movement relative to each other. This keeper is formed upon a plate indicated at 9, and the latter may be provided with suitable openings through which screws 10 may be passed to secure the plate firmly upon the rail 6. In the present instance, the inner or beveled surface of the rail 6 is cut away or channeled as at 11 to receive the plate and keeper, so that the latter will be disposed entirely within the channel and will present no obstruction to preclude proper meeting of the beveled surfaces of the sash rails. Furthermore, this channeled arrangement enables the keeper plate to be applied to the sash rail in proper vertical position. The keeper includes a beveled or inclined face 12, terminating at one end in an abrupt shoulder 13; this shoulder being disposed at the lower end of the keeper.

The rail 7 is provided with latch mechanism to engage with keeper 8 to maintain the sashes properly fastened in closed position. The mechanism for accomplishing this result includes a latch indicated generally at 14 pivotally carried by the rail 7 and with which is associated means for extending the latch to engage the keeper 8 as well as means whereby the said latch may be manually retracted when it is desired to raise or unlock the window. The latch 14 includes a plate 15 having trunnions 16 at its lower end and projecting outwardly therefrom to engage and lock in bearings 17 within a housing 18 carried by the bar or rail 7. The outer surface of plate 15 carries a lug 19 providing at its upper end an abrupt shoulder 20 to engage and lock be-

hind the corresponding shoulder 13 of keeper 8. The lug 19 is also provided with a beveled face 21 inclined in the same general direction as the beveled face 12 of the keeper, and is adapted to ride upon the said face of the keeper. The housing 18 may be formed of suitable metal, and is provided at its inner end with a base plate 23 having screws or other securing elements 24 passed therethrough to firmly hold the casing or housing to the rail 7. The bearing members 17 are arranged wholly within the housing 18 and at the ends thereof, and the plate 14 is therefore wholly confined by the housing. 15 The lug 19 of the latch member projects through an opening 25 in the outer surface of the housing.

The rear surface of plate 15 of the latch is provided with a hollow boss 26 having oppositely disposed notches 27 therein to receive pins 28 projecting laterally from the inner extremity of a latch controlling rod 29. This rod passes rearwardly through the base plate 23 of the latch housing and through an opening 30 formed in the rail 7, and is provided at its opposite or outer end with a knob 31 by means of which the rod may be conveniently manipulated. 25 That portion of the rod 29 which is confined within the housing 18 is encircled by an expansion spring 32, one end of the said spring engaging within the boss 26, while the opposite end of this spring bears against the base plate 23 of the housing. 30 This last-mentioned end of the spring is confined within an annulus 33 projecting inwardly from the base plate 23. The spring 32 thus exerts pressure upon the latch to normally maintain the latter in extended or locking position, yet this latch may be readily retracted by pulling upwardly upon the rod 29. The grooves or recesses 27 in the boss 26 incline in opposite directions, so that the pins 28 carried by the inner end of the rod may be readily engaged therein and yet can not become readily detached from the housing. However, should it be desired to withdraw the pin from the latch, it is but necessary to rotate 45 the pins slightly in one direction to cause said pins to ride out of their respective slots.

The interior face of rail 7 is channeled or recessed and receives a liner 35 formed of suitable metal, the latter having flanges 36 projecting outwardly from its edges, and through which retaining screws or other securing elements 37 may be passed to firmly hold the liner to the rail. The rod 29 for operating the latch is of such length 50 that when the latch 14 is moved inwardly to its locking position, by action of spring 32, the knob or head 31 of the latch bar will be wholly confined within the liner 35 and will thus provide no projections.

65 To operate the device in unlocking the

window, it is but necessary to grasp the knob 31 and apply rearward pressure, whereupon the latch 14 will swing rearwardly upon its trunnions 16, withdrawing lug 19 from beneath the abrupt shoulder 13 of keeper 8. 70 When thus withdrawn, the window may be opened, and immediately upon release of knob 31, the spring 32 will move the parts back to normal or operative position. When the meeting rails of the sashes are properly brought together in closed position, the lug 19 will be engaged behind the keeper 8 so as to firmly hold the sashes in locked position, and it will be understood, of course, 75 that the keeper and locking lug are so positioned upon their respective sashes that this locking action will only take place when the sashes have been brought properly and securely together.

From the foregoing it is obvious that I have provided sash fastening mechanism which is of extremely simple construction and yet which will prove thoroughly reliable and effective in practice. By equipping the window with locking mechanism of this character, the unsightly latches heretofore proposed are dispensed with, and all of the locking means are properly hidden from view. By embedding the locking mechanism in the rails or bars as thus proposed, the lock mechanism will be obscure from the view of burglars or others attempting to unauthorizedly open the window, and furthermore, this secure housing of the lock mechanism obviates the necessity of the lock mechanism heretofore used upon the upper rail of the inner sash, and which have proven extremely objectionable not only in their unsightly appearance but because of their defacing the window framing when the lower sash has been raised to its topmost limit. 100

While the above is a description of the invention in its preferred embodiment, it will be understood that various changes in the construction and arrangement of parts may be resorted to if desired, without departing from the spirit of the invention as defined by the claims.

Having thus fully described my invention, I claim:

1. In a window latch, the combination of upper and lower sashes having meeting rails provided with inclined abutment surfaces, said surfaces having cut away portions forming recesses with straight vertical inner walls, a keeper member disposed within the recess of one of said rails and comprising a plate secured to the inner wall thereof and having a latch lug provided with a beveled face and a shoulder, a latch member disposed within the recess of the other rail and comprising a base plate secured to the inner wall thereof, said base plate having a housing projecting therefrom beyond the line of said recess and adapted to extend into the recess of 120

the first-named rail when said rails are in alinement, a latch pivotally mounted within said housing and carrying a latch lug having an inclined face and a shoulder for cooperation with the inclined face and shoulder of the keeper member, a longitudinally movable rod upon the rail carrying the latch member having an outer end portion projecting into said housing and pivotally connected with 10 said latch, a coiled spring disposed about said outer end portion of the rod between the base plate of the latch member and the latch for normally holding the latch projected, and an operating knob upon the inner end of 15 the rod.

2. In a window latch, the combination with the meeting rails of window sashes, of a keeper carried by one of said sashes, a latch member carried by the other sash and movable into or out of engagement with 20 said keeper, a longitudinally and rotatably movable rod, and a pivotal connection between said rod and the latch member, whereby the latch member may be moved into or 25 out of engagement with said keeper through longitudinal movements of said rod, said pivotal connection including coacting surfaces on the inner end of the rod and outer side of the latch member, engageable and 30 disengageable with each other through reverse rotary movements of said rod.

3. In a window latch, the combination with the meeting rails of window sashes, of a keeper carried by one of said rails, a latch 35 member pivoted upon the other rail and adapted to engage and lock with said keeper when the rails are brought together, an annular boss on the latch member having diametrically disposed inclined notches, a 40 longitudinally movable and rotatable operating rod for said latch member, and laterally projecting pins carried by said rod and seated in said inclined notches in the boss, whereby the latch member is pivotally connected with the rod for swinging movements 45 under longitudinal movements of said rod, and whereby through rotary movements of the rod the pins may be engaged with or disengaged from said notches to couple the 50 rod to or uncouple it from the latch member.

4. In a window latch, the combination

with the meeting rails of window sashes, of a keeper on one of said rails, a base plate on the other rail carrying a housing, a latch pivotally mounted in said housing and provided with an annular boss having diametrically disposed inclined notches, an operating rod having an inner end portion extending into said housing through said base plate, pins upon the outer end portion of the rod 55 detachably and pivotally engaging said notches in the boss, a coiled spring encircling the outer end of the rod between the base plate and said pins, and a knob upon the inner end of the rod.

5. In a device of the class described, the combination with meeting sash rails, of a keeper carried by one of said rails, a housing carried by the other rail and having an opening therein, a latch plate pivotally 70 mounted in said housing, a lug carried by said plate and adapted to extend through said opening to engage said keeper, a hollow boss on said latch plate having inclined notches in the edges thereof, a rod extending through the sash rail and into said housing, pins carried by said rod and detachably engaged in said recesses, a spring interposed between said housing and said latch plate, and an operating knob on the outer end of said rod. 75

6. In a device of the class described, the combination with meeting sash rails, of a keeper carried by one of said rails, a housing carried by the other rail and having an opening therein, a latch plate, trunnions 80 upon said latch plate, bearing members in said housing, a lug carried by said plate and adapted to extend through said opening to engage said keeper, a hollow boss on said latch plate, the said hollow boss having inclined notches in the edges thereof, a rod extending through the sash rail and into said housing, pins carried by said rod and detachably engaged in said recesses, a spring 85 interposed between said housing and said latch plate, and a knob on the outer end of said rod; the said knob lying wholly within the surface of the sash rail when the latch plate is projected.

In testimony whereof I affix my signature.

STEPHEN R. FETNER.
